UNITED STATES PATENT OFFICE.

JACOB KNITTWEIS, OF PHILADELPHIA, PENNSYLVANIA.

FIREPROOF WINDOW.

No. 833,061.

Specification of Letters Patent.

Patented Oct. 9, 1906.

Application filed April 26, 1906. Serial No. 313,827.

To all whom it may concern:

Be it known that I, JACOB KNITTWEIS, a subject of the German Emperor, residing in Philadelphia, Pennsylvania, have invented 5 certain Improvements in Fireproof Windows, of which the following is a specification.

One object of my invention is to provide a construction of window-frame and sashes, 10 such that either one or both of said sashes may be easily removed from the frame in order that the outside surface of the window-glass may be cleaned without the necessity for the cleaner being outside of the window.

15 A further object of the invention is to provide counterbalance-weights for the sashes, frictional retarding means for the sash-weights, and a fusible device for releasing said retarding means to permit the counter- 20 weights to cause closing of the sashes in the event of a rise of temperature in their vicinity such as would be caused by fire, the device as a whole being designed to cause both the upper and lower sashes to automatically 25 move to and remain in their closed positions in the event of such abnormal temperature rise.

These objects I attain as hereinafter set forth, reference being had to the accompanying 30 drawings, in which—

Figure 1 is a vertical section of a window-frame and its sashes, illustrating in detail my invention as applied thereto. Fig. 2 is a plan view of the structure shown in Fig. 1. 35 Fig. 3 is an end elevation of certain of the sash-controlling mechanism illustrated in Figs. 1 and 2. Fig. 4 is a horizontal section, 40 on an enlarged scale, illustrating the detail construction of a portion of the sash structure. Fig. 5 is a side elevation of a form of hook which may be used to force the guiding-section of the sash into the side member thereof in order to permit said sash to be 45 swung on its horizontal pivots, and Fig. 6 is a perspective view illustrating in detail certain of the mechanism for guiding the movable side portions of the sash.

In the above drawings, A represents a fire-proof window-frame of sheet metal provided 50 with hollow side sections for the reception of sash-weights b and b' , respectively belonging to the lower and upper sashes. The inner vertical faces of said side members are provided with vertically-extending sash-guide- 55 ways a and a' , of which the first is designed to receive the lower sash B and the second to

receive the upper sash B'. Said sashes, as is customary, have hollow top, bottom, and side members and are formed for the reception of glass panes b^2 . Extending longitudinally within each hollow side member is a sheet-metal casing b^3 , open on the face adjacent to the window-frame and having inwardly-projecting flanged portions b^4 . These latter are extended outwardly to form the bearing-surfaces of the side members of the sash, being finally bent at right angles to said surface and rigidly clamped or held to the main sheet metal of said side members.

Extending longitudinally within the guide-ways a and a' of the window-frame are trough-shaped guide-sections D, also of sheet metal, one for each side member of each sash and of substantially the same length thereas. These guide-sections are outwardly flanged 75 along their longitudinal edges, as shown at d , so as to engage the inwardly-flanged portion b^4 of the internal casings b^3 . Each section D is, moreover, free to move bodily into and out of its casing b^3 from the position shown in 80 full lines in Fig. 4 to the position shown in dotted lines, there being links d' extending between and pivoted to the inner surface of the casing and also pivoted to blocks d^2 , fixed in any desired manner to the inside surface of 85 the guide-section D. A metallic block b^5 is slidably mounted in a slot in the inner portion of the casing b^3 at approximately its middle point, and from this there extend rods b^6 , loosely connected to said block b^5 as well as 90 to the blocks d^2 , which, as above noted, are fixed to the guide-section D. Also projecting from each block b^5 of the lower sash is a pin or pintle b^9 , to which is pivotally attached one end of a chain or cable b^7 , connected to the sash-weight b . Similar chains b^8 connect the similar pivot-pins of the upper sash B' with the corresponding weights b' .

It will be understood that mechanism similar to that described is provided for each side 100 of the upper and lower sashes B and B', it being noted that the sash-weights b for the lower sash are of such a mass that in the absence of the device hereinafter described they will be overbalanced by said sash, being 105 insufficient to maintain the latter in its raised position. The weights b' for the upper sash, on the other hand, are of such a mass that they overbalance said sash, and similarly in the absence of the device herein- 110 after described will move it to and maintain it in its closed position.

The device above referred to for normally maintaining the sashes in any position in which they may be placed consists in the present instance of a casting E, placed one on each of the upper side portions of and within the hollow window-frame. Upon each casting are suitably journaled the two pulley-wheels e and e' for the reception of the chains or cables connecting the sash-weights with their respective sashes, and there is for said two pulley-wheels e and e' a brake-shoe e^2 , placed to bear upon them and fixed to and guided by a rod e^3 . This rod has connected to it one end of an upwardly-extending spring e^4 , the other end of which is attached to a chain or cable e^5 , passing upwardly and around a curved or bent-up portion of the metallic frame. The upper end of this chain e^5 is connected to a link through which loosely passes the central portion of a second chain or cable e^6 , whose ends are attached, respectively, to a pair of independently-revolvable spindles F, each spindle, therefore, having connected to it one end of each chain e^6 , coming from opposite sides of the window-frame. Said spindles F project through the respective faces of the top members of the window-frame and are squared at their ends for the reception of a wrench or crank whereby they may be turned. In addition each of these spindles has fixed to it a plate or disk f, projecting through the lower horizontal surface of the top member of the window-frame, as shown in Fig. 1. There are in the periphery of each plate a series of small holes adapted to receive a pin or plug f' , composed of metal designed to fuse at a predetermined and relatively low temperature and so placed as to engage the window-frame to prevent revolution of the plate.

In order to set the device, a suitable wrench is applied to the squared end of either one of the spindles, which is thereby turned so as to wind up one end of each of the chains e^6 , connected to it, and thereby cause tension to be exerted upon the chains e^5 and the springs e^4 , so as to force the brake-shoes e^2 against their respective sets of sash-pulleys with a force sufficient to prevent the lower sash returning to its closed position under the action of its weights b after it has been moved from such position. The action upon the upper sash is similar, since this also will now remain in any position in which it is placed, because of the pressure upon the sash-pulleys exerted by the brake-shoes e^2 in spite of the overbalancing tendency of the sash-weights b'. After sufficient amounts of the chains e^6 have been wound upon the spindle F to cause the brake-shoes to exert the desired tension upon their pulleys the pin f' is inserted in one of the holes in the plate f on said spindle, it being understood that a pin has previously been placed in the plate f of the other spindle, the fusible pins in both

cases being inserted in that portion of the plates projecting through the face of the window-frame. If now the temperature of the atmosphere or metal in the vicinity of either of the pins f' be raised above the predetermined point at which the pins f' fuse—as, for example, by a fire—said pins will melt, thereby releasing the brake-shoes from frictional engagement with their respective pulleys. Under such conditions, owing to the unbalanced state of the various sashes, these will automatically return to their closed positions, since the lower sash overbalances its weights, while the upper sash is overbalanced by its weights.

In order to swing one of the sashes upon its pins b^6 as an axis, so as to obtain access to the outside surface of the glass, I raise the lower sash, for example, and by inserting hooks, such as that shown at G in Fig. 5, through opening g in the lower ends of each guide-section D and pulling downwardly on said section I cause these latter to move into the casings b^3 under the action of the connecting-links d' and rods d^6 . In order to permit of this action, the blocks b^5 slide in their slots, it being understood that the connection between the rods and their adjacent parts is such as to cause the said guide-section to each move parallel to itself. The guide-pieces D are thus brought into the positions shown in dotted lines in Fig. 4, with their outer edges free of the guideways in the sash-frame, so that the sash B may be revolved upon its pins b^6 as an axis, there being, preferably, bearing-pieces b^{10} attached to the lower ends of the chains b^7 for the reception of the heads of said pins. After the necessary cleaning of the glass has been accomplished the sash is returned to its normal vertical position, when, owing to its own weight, it moves bodily downward relatively to the guide-sections D, which are connected to the block b^5 and to the end of the sash-chains, the links d' moving on their pivots to permit of this action. By this downward movement the top and bottom portions of the guide-sections are forced outwardly into the guideways of the sash-frame, and the sash is then in condition for operation as before.

I claim—

1. The combination of a window-frame, a sash movable therein, a counter weight or weights having a flexible connection attaching it to said sash and so proportioned relatively to the sash as to cause it to automatically return from its open to its closed position unless otherwise prevented, with means operative on said flexible connection for maintaining the sash in any position in its frame to which it is moved, substantially as described.

2. The combination of a window-frame, a sash movable therein, a counter weight or

weights having flexible connections with said sash and so proportioned relatively to the sash as to cause it to automatically return from an open to a closed position unless otherwise prevented, a pulley for the flexible connections, and means operative on the pulley for maintaining the sash in any given position in its frame, substantially as described.

3. The combination of a window-frame, a sash therein, weights for the sash, pulleys, chains passing over the pulleys and connecting the weights to the sash, the masses of the weights and sash being so proportioned as to cause said sash to automatically return from its open to its closed position unless prevented, braking mechanism operative on the pulleys, and a heat-responsive device for normally maintaining said braking mechanism in operative condition, substantially as described.

4. The combination of a window-frame, a sash therein, weights for the sash, pulleys, chains passing over the pulleys and connecting the weights to the sash, the masses of the weights and sash being so proportioned as to cause said sash to automatically move from its open to its closed position unless prevented, braking mechanism for the pulleys including shoes acting thereon, springs active to press the shoes into engagement with the pulleys, with a connection for maintaining said springs under strain, said connection including a body of fusible material whereby it may be released in the event of a predetermined rise of temperature, substantially as described.

5. The combination of a window-frame, two sashes therein, pulleys for the sashes, weights for the lower sash of a mass less than the same, weights for the upper sash of a mass greater than said upper sash, chains connecting said weights to their respective sashes, brake-shoes for the pulleys, a spring connected to each brake-shoe, and adjustable connections between the springs and the window-frame, with fusible material included in said connections for releasing the shoes from the pulley-wheels under conditions of abnormal rise of temperature, substantially as described.

6. The combination of a window-frame, two sashes therein, pulleys for the sashes, weights for the lower sash of a mass less than the same, weights for the upper sash of a mass greater than said upper sash, chains connecting said weights to their respective sashes, brake-shoes for the pulleys, a spring connected to each brake-shoe, and means connected to the springs for maintaining them in condition to press the shoes against the pulley-wheels, with fusible material included in said connecting means and there placed to permit the release of the shoes from the pulley-wheels in the event of an abnormal temperature rise on either face of

the window-frame, substantially as described.

7. The combination of a window-frame, a sash movable therein, a counter weight or weights connected to said sash and so proportioned relatively thereto as to cause it to automatically return from its open to its closed position unless otherwise prevented, with a frictionally-acting device operative on the connections between the counter weight or weights for maintaining the sash in any position to which it may be moved in its frame, substantially as described.

8. The combination of a window-frame, a sash movable therein, a counter weight or weights connected to said sash and so proportioned relatively thereto as to cause it to automatically return from its open to its closed position unless otherwise prevented, with a device placed to act on the connections between each counterweight and sash for retarding movement of the sash in the frame and maintaining it in any position to which it may be moved, and means for adjusting the amount of the retarding force exerted by said device, substantially as described.

9. The combination of a window-frame, a sash movable therein, a counter weight or weights connected to said sash and so proportioned relatively thereto as to cause it to automatically return from its open to its closed position unless otherwise prevented, with means including a heat-responsive device for maintaining the sash in any position in its frame to which it is moved, said device having members exposed on both faces of said frame, substantially as described.

10. The combination of a window-frame, a sash movable therein, a counter weight or weights having flexible connections with said sash and so proportioned relatively thereto as to cause automatic closing thereof, means for normally preventing closing of said sash including a pulley-wheel for the flexible connection, a brake-shoe operative thereon, a revoluble member, a second flexible connection between the brake-shoe and said member, with a piece of fusible material for normally preventing revolution of the member and for maintaining the brake-shoe in engagement with the pulley, substantially as described.

11. The combination of a window-frame, a sash movable therein, counterweights for the sash having flexible connections therewith, braking devices operative on the flexible connections, a revoluble member projecting through a portion of the window-frame, with flexible connections between the braking devices and said revoluble member, and a plug of fusible material for preventing revolution of the member and maintaining the braking devices in condition to retain the sash in any given position in the frame, substantially as described.

12. The combination of a window-frame, a sash movable therein, counterweights for said sash so proportioned as to return the same from an open to a closed position unless otherwise prevented, braking mechanism for normally preventing such action, said mechanism including two revoluble spindles, a disk for each spindle respectively projecting through portions of the window-frame, on opposite faces thereof, there being holes in each disk, and plugs of fusible material fitting one of said holes for preventing revolution of the disks, two chains having their ends respectively connected to each spindle, a spring attached to each chain, with a friction-producing device connected to each of said springs and operative to prevent movement of the sash, substantially as described.

13. The combination of a window-frame, a sash movable therein, a pulley-wheel on each side of the sash, sash-weights having flexible connections with the sash respectively extending around said pulley-wheels, brake-shoes for the pulley-wheels, a spring attached to each brake-shoe, a chain connected to each spring and made in two parts, of which one is free to move relatively to the other, two independently-revoluble spindles each having connected to and wound upon it one end of each chain, disks on said spindles respectively projecting through opposite faces of the window-frame, there being holes around the periphery of said disks, and plugs of fusible material constructed to enter any of said holes and retain the disks in position to cause the brake-shoes to frictionally bear upon the pulleys, substantially as described.

14. The combination of a window-frame, a sash vertically movable therein, each side sash member being provided with a face portion movable toward and from it, a sash-weight for each side of the sash, and a flexible connection between said weight and said face portion, with means for causing said face portions to be normally maintained in their outer positions by reason of the weight of the sash, substantially as described.

15. The combination of a window-frame, a sash member therein having side members provided with face portions normally extending into the window-frame but movable into

said side members to permit removal of the sash, sash-weights having flexible connections with said face portions, there being a pivot-pin interposed between the flexible connection and each face portion, and links connecting each face portion with its side sash member, substantially as described.

16. The combination of a sash having hollow side members provided with longitudinally-extending and inwardly-projecting flanges, face portions for each side member movable into and out of the hollows thereof, a window-frame for said sash provided with guideways for the reception of said face portions, sash-weights, flexible connections attaching said weights to the respective face portions, links movably connecting the face portions to the sash, and a pivotal connection between each face portion and its flexible connection, substantially as described.

17. The combination of a sash having hollow side members, a face portion for each side member movable into and out of the same, links connecting each face portion with the sash, a pivot-pin movably connected to each face portion, sash-weights for the sash, chains connecting the sash-weights with the respective pivot-pins, and a window-frame for the sash having longitudinally-extending recesses for the reception of the face portions, said links being constructed to cause the face portions to be projected to their outer positions by the weight of the sash, substantially as described.

18. The combination of a sash having relatively movable face portions for its side members, links pivotally connecting the top and bottom of each face portion with its side member, a pivot-pin for each face portion, rods loosely connecting said pin to the top and bottom of the adjacent face portion, sash-weights flexibly connected to the pivot-pins, with a window-frame for the sash and said weights, substantially as described.

In testimony whereof I have signed my name to this specification in the presence of two subscribing witnesses.

JACOB KNITTWEIS.
